[57] CLAIM

The ornamental design for a seat for self-contained breathing apparatus, as shown.

DESCRIPTION

FIG. 1 is a perspective view of a seat for self-contained breathing apparatus showing our new design; FIG. 2 is a top plan view of the seat shown in FIG. 1; FIG. 3 is a right side elevational view of the seat shown in FIG. 1;

FIG. 4 is a front elevational view of the seat shown in FIG. 1;

FIG. 5 is a rear elevational view of the seat shown in FIG. 1; and,

FIG. 6 is a bottom plan view of the seat shown in FIG. 1.

The broken lines shown in FIGS. 1, 2, and 4 are shown to indicate conventional stitching.
